(57) **CLAIM**

The ornamental design for a light, as shown and described.

DESCRIPTION

FIG. 1 is a front view of one embodiment of a light that has the design.

FIG. 2 is a left side view of the light seen in FIG. 1.

FIG. 3 is a back view of the light.

FIG. 4 is a right side view of the light seen in FIG. 1.

FIG. 5 is an end view of the light seen in FIG. 1. The opposite end view is a mirror image of this view.

FIG. 6 is a perspective view showing an end, a side, and the back of the light.

FIG. 7 is a perspective view showing an end, a side, and the front of the light.

FIG. 8 is a front view of a second embodiment of a light that has the design.

FIG. 9 is a right side view of the light seen in FIG. 8.

FIG. 10 is a back view of the light.

FIG. 11 is a left side view of the light seen in FIG. 8.

FIG. 12 is an end view of the light seen in FIG. 8. The opposite end view is a mirror image of this view.

FIG. 13 is a perspective view showing an end, a side, and the back of the light; and,

FIG. 14 is a perspective view showing an end, a side, and the front of the light.

The broken lines show portions of the light that form no part of the claimed design.
